(57) **CLAIM**

The ornamental design for an earbud, as shown and described.

DESCRIPTION

FIG. 1 is a top perspective view of an earbud showing our new design; a mirror image earbud is evident from the earbud shown;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The dashed broken lines depict portions of the earbud that are for illustrative purposes only and form no part of the claimed design.

1 Claim, 7 Drawing Sheets
